T. Bruff, Sr.
Tooth Extractor.
Patented June 28, 1797.

NO PRINTED SPECIFICATION AVAILABLE

specification. This instrument has a double claw with a joint near the mid-hand and a spring to draw them together when set on the tooth. It has a following with two handles, one to answer as a handle for the left hand to keep it on the adjacent tooth, the other having a hook on the upper part of the end, answering as a guide and support to the lever which passes through the staple at the extreme end, and the point through the eye of the claw—under the following is a crooked cap (flaking cap) with a curved hand and turning on a pivot) made to the left to suit the size and shape of the jaw. There is another cap made long designed to set on the front and back teeth, equally having a hole through the mouth large enough to draw the claw through. The lever has a handle like the common key instrument. It has a crooked blade near the extreme end to raise it perpendicular from the following when turned by the handle; it passes through the hook of the following to the handle, which is about two inches from the handle, the front being small and round passes through the eye of the claw (which is sharp at the top), and by a curve in the back of the blade brings out the tooth in a perpendicular direction.
